UNITED STATES PATENT OFFICE.

CHARLES ANDERSON AND JAMES OLIVER, OF SOUTH BEND, INDIANA,
ASSIGNORS TO THE SOUTH BEND IRON WORKS, OF SAME PLACE.

PLOW.

SPECIFICATION forming part of Letters Patent No. 275,972, dated April 17, 1883.

Application filed January 25, 1883. (No model.)

To all whom it may concern:

Be it known that we, CHARLES ANDERSON and JAMES OLIVER, of South Bend, in the county of St. Joseph and State of Indiana, have 5 invented certain new and useful Improvements in Plows; and we do hereby declare the following to be a full, clear, and exact description of the invention, such as will enable others skilled in the art to which it pertains to make 10 and use the same.

Our invention relates to an improvement in plows of the type furnished with reversible points and shares. Heretofore reversible points have been secured in place by means of bolts and 15 nuts. Such forms of attachment in this type of plows are objectionable for various reasons. In order to detach or replace a reversible point secured by a bolt and nut, the plow must be turned bottom side up, and this necessitates 20 detaching the team or double-trees. Again, a wrench or hammer is necessary to unscrew the nut, and it is often the case that considerable time is wasted in procuring such tool. Further, when the parts are new the nuts are liable to 25 work loose and fall off the bolt while the plow is in use and cause delay in the replacing of a new nut; or, if the nut has remained secure for any length of time, it is liable to rust fast on the bolt, so that in attempts to remove it the 30 bolt is stripped or twisted off.

The object of our invention is to obviate the defects and objectionable features in plows provided with reversible points, as above noted, and to secure reversible points in place without 35 the use of fastening-bolts and nuts.

A further object is to provide a reversible point and plow-standard of such construction that the point may be firmly secured in place.

A further object of our invention is to provide an improved construction of reversible plowshare.

With these ends in view our invention consists in certain features of construction and combinations of parts, as will hereinafter be 45 explained, and pointed out in the claims.

In the accompanying drawings, Figure 1 is a view in perspective of our improved plow. Fig. 2 is a view in side elevation. Fig. 3 is a plan view of the under side of the plow. Fig. 4 is 50 a similar view with the point removed. Fig.

5 is a front view of the plow with the point removed. Fig. 6 is a vertical longitudinal section, showing the devices for locking the point in place. Fig. 7 is a detached view of the locking-lever. Fig. 8 is a view in side elevation of 55 the plow-point. Fig. 9 is an end view of the same. Fig. 10 is an edge view of the share. Fig. 11 is a view in perspective of the same; and Figs. 12 and 13 represent a modification.

A represents the standard, B the mold-board, 60 and C the landside, the forward portion of the latter being secured within a recess, a, in the landside of the standard, so that the outer surface of the landside will be flush with the landside b of the standard-foot D. The upper face of the foot of the standard is formed with a groove, E, and sufficiently broad side walls, e e', to afford ample bearings for the upper side of the reversible point. This groove extends beneath the mold-board, as shown. 70

F is the wing of the standard-foot, and is depressed, so as to form a rear wall, f, and a side wall, f', the purpose of which will be herein-after described. The under side of the foot is also provided with a groove, F', and with side 75 walls, e', corresponding in width to the upper walls, e e'. The groove F' extends rearward beneath the overlapping web G, the outer end of which connects with the landside G' of the standard, and its inner end with the flange g, 80 which constitutes a side bearing for the plow-point, and with the curved wall g', which is formed integral with the mold-board side g' of the standard. It will thus be observed that the web G, together with the curved wall g' 85 and the landside G' of the standard, forms a sole for the standard and an inclosed and protected recess, G', in rear of the standard-foot. The nose of the standard-foot is provided with an open slot, g'. 90

The reversible point H is formed with correspondingly-tapered faces h and sides h', and consists of the solid point H', the rearwardly-projecting flanges H'', and the prongs H''. The inner or adjacent sides of the flanges are of 95 T form, the ribs I being constructed to fit within the grooves E and F' in the foot of the standard, while the flat or practically flat bearings i fit correspondingly-shaped bearings on the standard-foot. The ribs I merge together 100

at the point I' , which portion fits within the open slot g^3 in the nose of the standard. One edge of the flange, situated beneath the foot, bears against the flange g , while the rear end, j , of the flange abuts against the front edge, j' , of the web G , and the rear end, j^2 , of the flange that is uppermost fits against the lower edge of the mold-board.

- The prongs H^3 are a continuation of the ribs I , and are provided with notches J , each of which is beveled on opposite sides, as shown at $k k'$. The prongs H^3 extend into the recess G^2 , the upper prong fitting beneath the lower edge of the mold-board, while the lower prong bears on the upper surface of the web G . From the foregoing it will be observed that the reversible point is insured an extended bearing of such a character as to be prevented from accidental vertical or lateral displacement, the mold-board is relieved from shocks received by the point, and the flanges of the point are prevented from spreading; and, further, those ends are secured in a strong and most durable construction of parts. On the inner side of the standard are formed the lugs $L L'$, between which is pivoted the lever M , having a T-shaped head, M' , with beveled sides $m m$. Lever M is released in its locked position by means of the spring l . To secure the point in place pressure is applied to the arm m' of the locking-lever and the point forced rearward to its seat. The lever is then released, allowing the head M' to engage in the notches J of the prongs. Owing to the beveled faces on the sides of the notches and the head of the locking-lever, the latter will engage the point, though the castings may not exactly fit each other, and retain the point against longitudinal displacement. By this construction and arrangement of parts a point may be reversed or replaced without turning the plow upside down or detaching the team or double-trees, and without the use of a wrench, hammer, or other tool. Again, the point is held firmly in place, and the employment of bolts and nuts as fastening devices is obviated. Many changes in the construction and form of the parts might be resorted to. The ribs on the reversible point may be semicircular, square, V-shaped in cross-section, and correspondingly-formed grooves provided in the foot of the standard. The ends of the flanges of the point may be beveled, so as to fit beneath the mold-board and over the edge of the overlapping web on the under side of the standard. The shape of the locking-lever may be varied. Instead of having notches on the inside of the prongs, they might be located on the outside and the head of the lever constructed to engage therewith. Instead of using a spring, a set-screw might be inserted through the outer end of the lever and arranged so that by turning the set-screw in one direction the locking-head would be free to move outward and release the prongs, while a reverse movement would force the locking-head in engage-

ment with the notches in the prongs. Many other changes in the construction and arrangement of parts might be resorted to without departing from the spirit of our invention.

O represents the reversible share, which is made with the cutting-edge o , inwardly-inclined ends o' , and rear edge, O' , the latter being preferably of about double the thickness of the lower edge of the mold-board, and supported in the depressed seat on the wing of the standard. The object of making the rear edge of the share of such increased thickness is to enable it to be reversed, and also preserve the proper lines and curves of the mold-board and share. We do not restrict ourselves to any particular relative thickness of mold-board and share, as they may be varied according to the character or type of the plow; but to insure the desired curves and lines it is necessary to form the share of increased thickness at its rear edge and support it in a sunken seat on the wing of the standard. Opposite sides of the share are beveled, as at $P P'$, and bent, as shown at P^2 , in order to cause that portion of the share located adjacent to the point to come up even therewith and form a smooth surface, and one that will scour when the point will.

In Figs. 12 and 13 the point is shown with its prongs only about half the width of the flanges, and arranged to form shoulders which abut against the standard, and thus relieve the thin point of the standard from undue strain. The prongs extend through the openings in the bracket Q of the standard, and are retained in place by the T-head of the spring-lever. This construction insures a bearing for the upper and lower flanges of the point, which will serve to relieve the thin point of the standard from all undue strain, both vertical and lateral.

Having fully described our invention, what we claim as new, and desire to secure by Letters Patent, is—

1. The combination, with a standard and a reversible plow-point, of a spring-actuated locking-lever for securing the point against displacement, substantially as set forth.
2. The combination, with a standard and a reversible plow-point having notched prongs or jaws adapted to be inserted through openings formed in the standard, of a locking-lever adapted to engage in the notches of said prongs or jaws, substantially as set forth.
3. The combination, with a standard and a reversible plow-point having notched prongs or jaws extending rearwardly from the point, and adapted to be inserted through openings formed in the standard, of a locking-lever having its head constructed with beveled surfaces adapted to fit the correspondingly-beveled surfaces of the notches in the prongs or jaws, substantially as set forth.
4. The combination, with a plow-standard having its foot provided with grooves on its upper and lower sides, of a reversible plow-

- point constructed with T-shaped flanges that fit within the grooves in the foot of the standard, substantially as set forth. 30
5. The combination, with a standard having grooves formed on the upper and lower sides of its foot portion and a web on the lower portion of the standard, and in rear of the grooved foot, of a reversible plow-point adapted to fit within the grooves in the standard-foot, and provided with prongs that extend through openings in the standard, substantially as set forth. 35
6. The combination, with a standard having a grooved foot and a web constituting a sole and forming a protected recess in rear of the foot, of a reversible plow-point having prongs that extend back into said recess, substantially as set forth. 40
- 15 7. The combination, with a standard having a grooved foot, of a reversible plow-point having prongs extending rearward from the ends of the flanges of the plow-point, the upper prong extending beneath the mold-board and the lower one between the foot and a web, substantially as set forth. 45
- 20 25 8. The combination, with a standard provided with grooves extending back to the mold-board, of a reversible plow-point having correspondingly-inclined flanges provided on their inner or adjacent faces with ribs that extend their entire length, substantially as set forth. 50
9. The combination, with the standard constructed with grooves on the upper and lower side of its foot portion and an open slot in the front edge thereof, of a reversible plow-point provided with T-shaped flanges that fit within said grooves and open slot, substantially as set forth. 55
10. The combination, with the standard and mold-board, of a reversible plow-point provided with prongs that extend beneath the mold-board and in contact therewith, substantially as set forth. 60
11. The combination, with the standard and reversible plow-point, of the reversible share having beveled faces on opposite surfaces at its opposite ends, substantially as set forth. 65
- In testimony whereof we have signed this specification in the presence of two subscribing witnesses.
